Des. 239,833
Patented May 11, 1976

239,833

FLEXIBLE ELECTRICAL CONNECTOR

Robert R. Rough, Jr., Toledo, Ohio, assignor to
Owens-Illinois, Inc., Toledo, Ohio

Filed Dec. 26, 1973, Ser. No. 427,965

Term of patent 14 years

Int. Cl. D13—03

U.S. Cl. D26—1 R

FIG. 1 is a front elevational view of the flexible electrical connector incorporating the design;

FIG. 2 is a rear elevational view of the flexible electrical connector design of FIG. 1 turned 180 degrees;

FIG. 3 is a side view taken from the left side of FIG. 1.
I claim:

The ornamental design for a flexible electrical connector, as shown.
